UNITED STATES PATENT OFFICE.

ARTHUR L. HALLIDAY, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,332, dated October 2, 1883.

Application filed August 3, 1883. Term of patent 3½ years.

To all whom it may concern:

Be it known that I, ARTHUR L. HALLIDAY, of Yonkers, in the county of Westchester and State of New York, have invented and produced a new and original Design for a Carpet, of which the following is a full description, in connection with the accompanying photograph, which represents a face view of my new design for a carpet.

10 This invention relates to a new configuration and arrangement of groups on the face of a carpet or analogous fabric.

In the accompanying photograph, the letter A represents a figure of fanciful outline, from 15 which projects a bifurcated stem carrying at one end a floral decoration, a, and at the other end a rosette-like figure, b. From the lower part of the figure A extends also a stem, which joins said figure to a group, B, of three oval 20 rosettes. Above this group B is a smaller rosette, d, and above that a larger fanciful figure, D, which resembles in its outline the figure A. From the figure D extends upwardly

a stem carrying a group of four rectangular figures, E. Between the rosette-like figure b 25 and the fanciful figure D is a larger oval rosette, F, which is connected by stem with the group B. Below the figure F is a cluster, G, of small ovals, which connects by a downwardly-projecting stem with an angular figure, e, 30 and by another stem with a fanciful figure, f. By another stem the group G connects with a cluster, H, of rosettes. On the background of the carpet are representations of detached leaves g g, each leaf consisting of a straight 35 stem with obliquely-extended leaflets. There are also a series of S-shaped figures, h, on the background of the carpet.

I claim—

The design for a carpet, the same consisting 40 of the figures A B C D E F G H a b d e f, substantially as shown.

ARTHUR L. HALLIDAY.
